(57) **CLAIM**

The ornamental design for a wearable band for facilitating hearing, as shown and described.

DESCRIPTION

FIG. 1 is a front elevation view of a wearable band for facilitating hearing.

FIG. 2 is a rear elevation view of the wearable band for facilitating hearing of FIG. 1.

FIG. 3 is a first side elevation view of the wearable band for facilitating hearing of FIG. 1.

FIG. 4 is a second side elevation view the wearable band for facilitating hearing of FIG. 1.

FIG. 5 is a top plan view of the wearable band for facilitating hearing of FIG. 1.

FIG. 6 is a bottom plan view of the wearable band for facilitating hearing of FIG. 1.

FIG. 7 is a first front perspective view of the wearable band for facilitating hearing of FIG. 1.

FIG. 8 is a second front perspective view of the wearable band for facilitating hearing of FIG. 1.

FIG. 9 is a first rear perspective view of the wearable band for facilitating hearing of FIG. 1.

FIG. 10 is a second rear perspective view of the wearable band for facilitating hearing of FIG. 1.

FIG. 11 is a front elevation view of a wearable band for facilitating hearing.

FIG. 12 is a rear elevation view of the wearable band for facilitating hearing of FIG. 11.

FIG. 13 is a first side elevation view of the wearable band for facilitating hearing of FIG. 11.

FIG. 14 is a second side elevation view the wearable band for facilitating hearing of FIG. 11.

FIG. 15 is a top plan view of the wearable band for facilitating hearing of FIG. 11.

FIG. 16 is a bottom plan view of the wearable band for facilitating hearing of FIG. 11.

FIG. 17 is a first front perspective view of the wearable band for facilitating hearing of FIG. 11.

FIG. 18 is a second front perspective view of the wearable band for facilitating hearing of FIG. 11.

FIG. 19 is a first rear perspective view of the wearable band for facilitating hearing of FIG. 11; and,

FIG. 20 is a second rear perspective view of the wearable band for facilitating hearing of FIG. 11.
